Specification for Design.

Patented Mar. 9, 1920.

Application filed April 23, 1919. Serial No. 292,175. Term of patent 14 years.

To all whom it may concern:

Be it known that we, KNUD J. W. FREITAG, a subject of the King of Denmark, and HOWARD D. AINSWORTH, a citizen of the United States, both residents of the city and county of San Francisco, State of California, have invented a new, original, and ornamental Design for a Pump-Overflow Pan, of which the following is a specification, reference being had to the accompanying drawing, forming part thereof.

Figure 1 is a perspective view of a pump overflow pan illustrating our new design.

Fig. 2 is a cross sectional view of the pump overflow pan.

We claim:

The ornamental design for a pump overflow pan as shown.

KNUD J. W. FREITAG.
HOWARD D. AINSWORTH.
